DESIGN.

H. COHN.

LIGHTING FIXTURE UNIT.

APPLICATION FILED JAN. 13, 1921.

58,884.

Patented Sept. 6, 1921.

Inventor
Harry Cohn
By his Attorney J. Barker

UNITED STATES PATENT OFFICE.

HARRY COHN, OF BROOKLYN, NEW YORK, ASSIGNOR TO HYGRADE LIGHTING FIXTURE CORPORATION, OF BROOKLYN, NEW YORK, A CORPORATION OF NEW YORK.

DESIGN FOR A LIGHTING-FIXTURE UNIT.

58,884.

Specification for Design.

Patented Sept. 6, 1921.

Application filed January 13, 1921. Serial No. 437,088. Term of patent 7 years.

To all whom it may concern:

Be it known that I, HARRY COHN, a citizen of the United States, residing at Brooklyn, in the county of Kings and State of New York, have invented a new, original, and ornamental Design for a Lighting-Fixture Unit, of which the following is a specification, reference being had to the accompanying drawing, forming part thereof.

The figure is an elevation of a lighting fixture unit.

I claim:

The ornamental design for a lighting fixture unit, as shown.

HARRY COHN.
